UNITED STATES PATENT OFFICE

KENNETH DAVIS, OF EBENSBURG, PENNSYLVANIA, ASSIGNOR, BY MESNE ASSIGNMENTS, TO PEALE-DAVIS COMPANY, OF WILMINGTON, DELAWARE, A CORPORATION OF DELAWARE

MECHANISM FOR SEPARATING INTERMIXED DIVIDED MATERIALS

Application filed March 25, 1925, Serial No. 18,112. Renewed October 11, 1930.

The invention relates to mechanism for separating intermixed divided materials of different specific gravities and more particularly to such a mechanism which is commercially operative and efficient in so separating intermixed materials through a wide range of sizes of the pieces or particles of the various materials, and wherein the difference in the specific gravities of the different materials is relatively small.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the constructions, arrangements and improvements herein shown and described.

The accompanying drawings herein referred to and constituting a part hereof serve to illustrate both the process and mechanical principles of the invention, and are illustrative but not restrictive of the invention.

Of the drawings:—

Fig. 1 is a plan view, partially diagrammatic, of a separating table of a particular shape or form embodying the invention;

Fig. 2 is a side elevation looking at the adjacent side of Fig. 1;

Fig. 3 is a transverse, vertical section, on an enlarged scale, taken on the line 3—3 of Fig. 1;

Fig. 4 is a fragmentary perspective view, with parts broken away, of the air box at the left-hand end of Fig. 1;

Fig. 5 is a somewhat diagrammatic view of the table reciprocating mechanism; and

Fig. 6 is a diagrammatic view similar to Fig. 1, showing the preferred air zoning but with the separating partitions omitted.

An example of intermixed materials, of relatively small differences in their specific gravities, and with the particles and pieces varying widely in size such as are successfully separated by my invention is a mixture of coal, "bony", rock, and other impurities, as it comes from the mine. The invention is well adapted for the separation of the intermixed

coal, bony and rock, as they come from the mine, and to effect a very thorough separation thereof, without previous "sizing", and my invention has been successfully commercially developed in this work.

The term "divided" is conveniently used to describe material in pieces or particles, the mine mixture just described being an example.

Heretofore, in all attempts to separate coal, bony and rock, and other impurities, it has been necessary to very closely size the materials by screening as a preparation for the separating action. A mixture having the range in sizes which I am able to successfully and practically completely separate without any previous screening or sizing whatsoever, in previous actual operations has been separated into approximately seven to ten sizes by screening before the separation of the materials is attempted. As an example of such screening required preparatory to separation by other tables, all sizes above 2 inches were screened out; from 2 inches to 1½ inches were screened as the next size; then from 1½ inches to 1 inch; from 1 inch to ½ inch; from ½ inch to ¼ inch; from ¼ inch to ⅛ inch; from ⅛ inch to ⅛ inch; and from ⅛ inch down were screened out on successive screens. Each of these sizes is then sent to a different separating table. Thus seven or eight different screens are required and seven or eight separating tables, one for each different size produced by screening, making about fourteen machines or mechanisms in all.

By my invention, I dispense with all of the screening mechanisms of the prior art and with all but one of the separating tables. I use only a single large separating table, and over this single table I send the unprepared, intermixed materials, which prior to my invention were necessarily sent first over the set of screening mechanisms, and then over the corresponding separating tables, as described in the preceding paragraph. I am able on this one table to practically completely separate the coal, rock and bony and other impurities from three inches in dimension of each material down to the finest dust.

My invention is applied to the separation

- of a continuous bed of the intermixed, divided materials, such as the unsized mixture of coal, bony and rock, the bed of materials undergoing separation being supported upon an air-pervious table, through which a blast of air is driven from beneath upwardly through the bed of material, the table at the same time being moved or reciprocated to mechanically forward the separated heavier element, which has settled upon the table, by friction and inertia toward a place of delivery, the gradation of the force of the air currents and the table structure cooperating in the novel manner hereinafter set forth to accomplish the desired result.
- The invention provides broadly for feeding on the material at a locus which is at or near the rear end of the separating table, and preferably entirely across this end, at such rate as to build up at the beginning and thereafter to continuously maintain upon the table a bed of materials of substantially uniform thickness, which moves gradually forward over the table. The materials undergo progressive separation as they move forwardly, gradually approaching complete separation, as they progress forwardly and laterally in the bed and upon the table toward places of delivery for the separated materials, and are completely separated before delivery.

The greatest air action through the bed of materials is in the area circumjacent to the point of feeding on the intermixed materials, the air action decreasing gradually, usually by comparatively small successive zones or areas, both forwardly and outwardly, along and over the table. These gradations in the air force action, or of the air perviousness of the table, as already stated, are also in a definite relation to the location and direction of extension of the separating partitions, which are fixed upon and project upwardly from the face of the table, the air force decreasing transversely outwardly with respect to the separating partitions. In the preferred form, also, the area or zones of varying air action extend forwardly in the general or approximate form of the arrangement of the separating partitions, the air force or action decreasing forwardly along the bed.

The separating partitions are vertical walls located upon and extending upwardly from the face of the table into the mass of materials upon the table and obliquely and transversely to the length of the table. The upward air currents and pressure loosen up the mass of material, that is, separates the pieces or particles from close contact and pressure together, and also floats or suspends, or impels upwardly, the particles of lighter specific gravity, and due to both of these concurrent influences or actions, the heavier particles settle down upon the surface of the table behind the separating partitions, while the

lighter particles, maintained in a higher position, or impelled or floated thereto, will pass over the tops of the separating partitions, and move along the general path of the travel of the bed of materials along or over the table. 70

Circumjacent to the place of feeding on the intermixed materials at the rear end of the table, the relatively more violent action of the air tends to greater separation or loosening up of the particles, and also effects 75 a stronger flotation or upwardly impelling force. The result is that the largest pieces of the heaviest material, such as rock settle to rest on the surface of the table behind the separating partitions at this point, all of the coal particles and the lighter rock particles being sustained at a sufficient height to pass over the partitions and to participate in the general movement of the bed of materials forwardly along the table. 80

The larger pieces of heaviest material, such as rock, which have settled upon the table, due to friction and inertia, slide forwardly along the table, but are guided or directed in their path by the particular separating partition 90 behind which they settle upon the table. It will be thus seen that both a separation, and a different directive action on the materials in so far as already separated, has been established or secured. 95

Considering the action now behind the next succeeding group of separating partitions, considered forwardly along the table, the air action being slightly decreased, the next larger pieces or next heavier particles of rock or other heavier material, that is, the next decreasing in size, will settle upon the table behind the adjacent separating partitions, and guided by the latter, will be impelled by friction and inertia forwardly along the table, at the same time being directed in their forward progression by the direction or location of the separating partition. Also the coal, and possibly the smaller pieces of rock, dependent on the intensity of the air action at 100 the particular place or area, will move onward over the tops of the partitions. 105

Thus by successive stages the particles of rock and other impurities, decreasing in size at each stage, will be separated and come to 115 rest upon the table, and will be impelled forwardly on the table by inertia and friction, and be directed by the separating partitions, while the layer of coal in the top of the bed will be continuously subjected to the 120 floating action of the upward air currents and pass over the separating partitions.

In the present preferred embodiment of the invention, the separated rock and impurities are subjected to an additional final 125 separating and cleaning action just prior to their discharge. The stream of rock which passes along the center of the table and discharges over the front end is caused to pass into an area of increasing air force as it moves 130

forwardly to the front end of the table whereby all the particles undergo a final loosening and stratifying action so that any remaining intermixed coal particles are floated to the 5 top and are not carried out with the discharging rock.

The accompanying exemplary drawings show the form of table in which I first commercially developed and successfully embodied my present invention, and commercially practiced my process. It will be understood, however, that my invention is equally applicable to tables of widely different shapes or forms.

15 In this present illustrated exemplary form, the table has an air-pervious deck 1. The means for effecting the zoning or different degrees of air current force in different areas of the table may be widely varied as found 20 expedient or desirable. For instance, a plurality of air chambers having different pressures may be provided beneath the table 1. In this present embodiment, table 1 comprises a plurality of perforated metal plates abutting 25 at their edges, the different degrees of force of the air currents being effected by variations or differences in the number or sizes of the holes in the plates of the table, or in both.

30 This table 1 structurally is carried upon a plurality of supporting bars or members 2, which in turn are carried upon a general frame 3, which may be channel iron and substantially of the contour of the outside of 35 the table, and may have also inner cross supports 4, likewise of channel iron.

The rear end 8 of the table may be of flat or straight transverse shape, the table extending forwardly and outwardly at an angle 40 from this point as shown at 9 and 10 to a place of greatest width 11, this being a median point, but preferably closer to the rear of the table. Up to this point the rear and side edges of the table are provided with 45 an upwardly-extending wall 12, which serves to retain the bed of material upon the table.

From this point the sides of the table incline angularly inwardly and forwardly, as shown at 13 and 14, toward and to the forward end of the table. Upon the surface of the table are placed a relatively large number of separating partitions 20, which preferably are spaced apart in parallel relation, and extend perpendicularly up from the 50 table. The partitions are inclined inwardly and forwardly, their inner ends terminating so as to leave a clear passage 21 along the center of the table between the inner ends of the separating partitions. At the side edges 55 of the table, there are preferably provided horizontally disposed shelves 22 and 23, just beyond the air pervious deck of the table, over which shelves the separated coal flows outwardly and is discharged. These shelves 60 maintain the thickness of the bed up to the

edges of the air pervious deck. Any desired form of means 19 may be employed for feeding the intermixed materials onto the bed at such variable or regulable rate as to maintain the bed of practically uniform thickness during the work of separation. The outside 70 separating partitions are preferably upwardly and forwardly inclined, as shown at 13^a and 14^a, to the height of the air box at the front end of the table.

At the forward end of the table is provided an air box, whereby air is directed inwardly from both sides and thereby throughout the entire mass of rock, or other heavier material, from the sides thereof, and also from above downwardly through the mass of rock, to serve as a final separation for any particles of coal remaining enmeshed in the rock. In the embodied form thereof a passage 30 for the discharge of the rock is provided, the bottom 31 of which is the table itself or preferably, an imperforate continuation thereof. The passage has also side walls 32 and 33, and a top 34, the bottom 31 being, as stated, preferably impervious to air, the sides 32 and 33 and the top 34 being air pervious. This structure is surrounded by an outer, air-confining chamber, having a rear wall 35, side walls 36 and 37, a front wall 38, and a top 39, there being an opening in the rear wall 35 which constitutes the mouth of the passage 30 at the front through which the rock is discharged. This passage is normally closed by a gate 41, pivotally hung at 42 and having removable 100 weights 43 or other means for varying the pressure on the gate.

As the stream of rock flows forward along the table, the air currents of this air box are blown therethrough and separate out from the mass of rock and will turn back upon the coal bed all final remaining particles of coal which may have reached this point. The gate 41 will swing open from time to time as the pressure of the rock accumulates, and permit the rock to flow out. That is, at the forward end of the stroke of the table, the inertia of the rock may or will increase the pressure against the gate, and the gate will swing open and a part of the rock will be ejected or permitted to slide out past the gate onto a delivery belt. By reason of the discharge of rock, the airblast backwardly and upwardly through the material will be increased, and will blow back any stray pieces of coal or other lighter material out of the mass of rock. There is preferably a gradual increase again in the air pressure upwardly through the bed for a short distance at the forward end of the table in front of the air box or place of discharge of the heavier material, as indicated in Fig. 1. This ultimate, gradually increasing pressure subjects the mass of separated rock at the front end of the table to a final 120 separating action. The increased air force is 125 130

strong enough to penetrate and loosen the particles in the mass of rock approaching discharge and to float any remaining particles of coal to the surface, where they are prevented from escaping with the rock and most effectively acted upon by the backward air blast from the air box.

Referring now to the zones of varying air pressure as shown more or less diagrammatically in Fig. 1 in their general relation to the length and breadth of the table, and in their preferred relation to the separating partitions in the illustrated form or shape of table, the boundaries of the zones are indicated by dotted lines, these sometimes running along or parallel to the separating partitions and sometimes crossing from one to another. The zones of different air perviousness, or air pressure, are graduated decreasingly from the greatest to the least and are correspondingly indicated by the letters A to F, the letter A indicating the area of greatest air currents or force, and F the area of least air force. The lines between the different areas or gradations of air force are indicated by letters a—b, corresponding to the letters A to F, already referred to. In certain parts of Fig. 1 it will be noted that the dotted boundaries of the different air force areas run along beneath the separating partitions. In accordance with one feature of the invention, the areas of varying or graduated air force or action are shaped generally to conform to the direction or position of the separating partitions along the table. It will be understood, of course, so far as concerns the principles of the invention that the sharply defined boundaries between the various air force or air action areas is merely a structural feature, and the gradations of air force may be varied gradually without any specific lines of demarcation between what may be termed units or steps of variation.

In Fig. 5 there is a general showing of one form of means for reciprocating the table and for creating an impact at the end of the forward reciprocating stroke of the table, should this be desired. This mechanism may be of any known or suitable form, and need not be described in detail. In this present embodiment, the table 1 has its general frame 2 and 3 mounted, by means of pairs of pivoted arms 50 and 51, on suitable supports on the upper edges of the side walls of the air chamber 52. A flexible, air-tight canvas connection 53 is placed between the air chamber and table. A spring 54 may be used to cushion and prevent too violent movement of the table. Stops 55 and 56 may be employed, the table striking thereagainst to give the required impact.

The means for reciprocating the table likewise may be of any suitable form. A shaft 58 is suitably journaled and driven, the shaft having actuating cams 59 thereon. Co-

operating cam rollers 60 are journaled in supports 51 carried upon the frame of the machine.

It will be understood that the air gradation arrangements, or air zoning, may be employed independently of the separating partitions. Accordingly, Fig. 6 is the same as Fig. 1, excepting that the separating partitions are omitted. The same reference characters are applied thereto as in Fig. 1, and further detailed description is unnecessary. It is preferable that the zones extend in the same general shape as the table itself, although this in detail may be varied as desired, within the scope of the invention, with different forms of table and to meet different characteristics and conditions of intermixed materials to be separated by the table. The reference numerals are applied to Fig. 6 in the same sense as they are applied to Fig. 1 and as used in the description thereof.

From all the foregoing it will be understood that mechanism and means are provided by the invention, realizing the objects and advantages herein set forth, together with other objects and advantages; and it will be further understood that departures may be made from the details of mechanism herein shown and described, within the scope of the accompanying claims limited only as may be necessary by the prior art, without departing from the principles of the invention and without sacrificing its chief advantages.

What I claim is:—

1. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, and means for longitudinally reciprocating the table.

2. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the sur-

face of the table and cooperating with the gradations of the air force in progressively separating the bed of intermixed materials, and means for longitudinally reciprocating the table.

5 3. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the surface of the table and cooperating with the gradation of the air force in progressively separating the bed of intermixed materials, the areas of varying air force being shaped generally in the direction of extension of the separating partitions, and means for longitudinally reciprocating the table.

4. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the surface of the table, and inclined inwardly and forwardly from the side of the table, and cooperating with the gradations of the air force in progressively separating the bed of intermixed materials and means for longitudinally reciprocating the table.

5 5. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the surface of the table, and inclined inwardly and forwardly from the side of the table, and

cooperating with the gradations of the air force in progressively separating the bed of intermixed materials, the areas of varying air force being shaped generally in the direction of extension of the separating partitions, and means for longitudinally reciprocating the table.

6. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the surface of the table, and inclined inwardly and forwardly from either side of the table and leaving an open unobstructed channel along the center of the table, and cooperating with the gradations of the air force in progressively separating the bed of intermixed materials, and means for longitudinally reciprocating the table.

7. A mechanism for separating intermixed divided materials which vary relatively very greatly in size and relatively very little in specific gravities which comprises an air pervious table, means for feeding the intermixed materials near the rear end of the table to maintain a bed of materials thereon undergoing progressive separation, said table having means for gradating the force of the air action therethrough decreasingly forwardly along the table away from said feeding means, but also increasingly for a short distance from the front end of the table, a plurality of separating partitions supported on and projecting upwardly from the surface of the table, and inclined inwardly and forwardly from either side of the table and leaving an open unobstructed channel along the center of the table, and cooperating with the gradations of the air force in progressively separating the bed of intermixed materials, the areas of varying air force being shaped generally in the direction of extension of the separating partitions, and means for longitudinally reciprocating the table.

8. A table for separating unsized intermixed divided materials including in combination the table deck, separating partitions upon the deck forwardly and transversely inclined, the deck being divided into zones of different air perviousness, in definite relation to the separating partitions and adapted to deliver air currents of gradually less intensity forwardly along the table, and hav-

ing an area of greater relative intensity of air action near the front end of the table.

9. A mechanism for separating intermixed divided materials including in combination an air-pervious table having separating partitions thereon extending forwardly and inwardly from either side toward the center line of the table, an unobstructed, central passageway for heavier material extending 10 longitudinally along the table between the ends of the separating partitions, means for reciprocating said table, means for passing lifting and loosening air currents therethrough, means for gradating the air action 15 decreasingly forwardly along said central passageway, a device for controlling discharge of heavier material at the front end of said passageway, and means for increasing the air action adjacent said discharge 20 device.

In testimony whereof, I have signed my name to this specification.

KENNETH DAVIS.
